UNITED STATES PATENT OFFICE.

WILLIAM ALONZO CHASE, OF MORRISVILLE, VERMONT, ASSIGNOR OF ONE-HALF TO FRED. B. LIVINGSTON, OF SAME PLACE.

INDICATOR FOR LAMPS, LANTERNS, &c.

SPECIFICATION forming part of Letters Patent No. 396,540, dated January 22, 1889.

Application filed March 21, 1887. Serial No. 231,724. (No model.)

To all whom it may concern:

Be it known that I, WILLIAM ALONZO CHASE, a citizen of the United States, residing at Morrisville, in the county of Lamoille 5 and State of Vermont, have invented certain new and useful Improvements in Indicators for Lamps, Lanterns, &c., of which the following is a specification.

My invention relates to improvements in 10 devices for indicating when an opaque lamp or other receptacle has been filled with liquid; and it consists in certain novel features, hereinafter described and claimed.

In the accompanying drawings, which fully 15 illustrate my invention, Figure 1 is a vertical central sectional view of a lamp provided with my improvement. Fig. 2 is a perspective view of the perforated cylinder, and Fig. 3 is a vertical section of the same.

My invention is designed especially for 20 application to lamps already in use and of any and all designs.

In the annexed drawings, A indicates the 25 body of a lamp having the feed-opening B in its top side, through which the oil is poured into the reservoir.

C designates a tube or cylinder made of 30 perforated material and having a closed lower end and an open upper end. The open upper end of the tube or cylinder is provided with the exterior screw-threads, G, by means of which it is secured in the feed-opening B.

Within the perforated cylinder or tube I 35 place a float, E, which is formed in the shape of a six-pointed cubical cross, of cork, light wood, or other material which will float on the illuminating-fluid. This float is also coated with luminous paint, in order that it may be seen in the dark.

From the foregoing description, taken in 40 connection with the accompanying drawings, it is thought the operation of the device will

be obvious. The illuminating-fluid is poured through the feed-opening in the usual manner, and passes into the cylinder and through the perforations therein into the reservoir or body of the lamp. As the oil rises the float will be carried upward, and when the lamp is full the upper point of the float will project through the feed-opening and notify the person using the lamp that a sufficient quantity of oil has been placed therein, as will be readily understood on reference to Figs. 1 and 3. I find that this form, while moving freely within the cylinder I, floats higher 55 upon the oil than other forms or dispositions of the material of the float, and always presents a luminous point upward.

It will be seen that I have provided a very simple and efficient indicating device which 60 can be readily applied to any style of lamp, and which can be manufactured and sold at a trifling cost.

I am aware that indicators have heretofore 65 been provided for lamps; but I do not claim such a device, broadly.

Having thus described my invention, what I claim, and desire to secure by Letters Patent, is—

The herein-described indicator for lamps, 70 consisting of a perforated cylinder or tube having a closed lower end and an open exteriorly screw-threaded upper end, and a luminous float within said cylinder in the form of a six-pointed cubical cross, substantially 75 as specified.

In testimony that I claim the foregoing as my own I have hereunto affixed my signature in presence of two witnesses.

WILLIAM ALONZO CHASE.

Witnesses;

JAMES C. ROBINSON,
ASAHEL M. BURKE.
